ELECTROMAGNETIC TRANSMISSION

Jacques Elwell, Courbevoie, France, assignor to
 Maag Zahnraeder & Maschinen Aktiengesellschaft, Zurich, Switzerland, a corporation

Application August 26, 1937, Serial No. 161,086
 In France September 7, 1936

11 Claims. (Cl. 171—322)

The present invention relates to a revolving mechanism comprising consumers of electric current, more particularly to lubricated gears having rotating electromagnets, whereby the current is transmitted to said consumers or electromagnets by means of a slip ring and a brush sliding thereon.

When using customary carbon brushes having a rotund or rectangular cross sectional configuration, the lubricating oil which cannot be prevented from reaching the slip ring forms a thin film between the ring and the brush and increases the electric transition resistance considerably. This resistance should be as low as possible because, for example in the case of electric motors, the voltage of the exciting current is relatively low. For example in the case of the starter motor in a motor car, the current is supplied by a battery and naturally not much tension is available to overcome high resistances. If the slip ring is protected against oil and held dry, then the brushes are worn out in a short time because, in order to reduce transition resistance, they must be forced to the ring with high pressure.

It is an object of the present invention to provide a brush which rests on the slip ring carrying an oil film with a ring shaped surface. With such a configuration of the contact surface of the brush, the electric transition resistance is very low and the life of the brush is long. This may be explained by the fact that the comparatively narrow annular surface presses the oil on a very short path outwardly or inwardly and away from the contact surface of brush and ring without necessitating extraordinary great pressure which would increase the wear on the brush.

In order to insure and control lubrication of the slip ring, the brush, according to the present invention, preferably is of tubular configuration and the lubricating oil is supplied to the interior of the brush. This supply may be carried out through openings in a socket in which the brush is slidably located. Any other lubrication of the slip ring, for example by spray oil, should be prevented.

With the apparatus according to the present invention, lubrication is maintained uniform and is easily controlled, the transition resistance of the electric current is held at a low figure, and the wear of the brushes is small and their life is long.

Further and other objects of the present invention will be hereinafter set forth in the accompanying specification and claims and shown

in the drawing which, by way of illustration, shows what I now consider to be a preferred embodiment of my invention.

In the drawing—

Figure 1 is an axial part cross sectional view of an apparatus according to the present invention.

Figure 2 shows part of what is shown in Figure 1 in large scale, the brush being shown in section.

Figure 3 is a longitudinal sectional view of a brush according to the present invention.

The apparatus shown is particularly suitable for use in motive power equipment.

Like parts are designated by like numerals in all figures of the drawing.

1 designates the casing into which shaft 2 extends. To shaft 2 a disc 21 is keyed which is provided with an annular rim 4 which carries a magnet winding 10. Rim 4 serves as electromagnetic coupling ring which, if excited, pulls the axially movable armature ring 3 towards itself and then rotates it, whereby the rotating power is transmitted by friction. The armature ring 3 may also be attracted by means of an annular electromagnet 5 having windings 8 and being rigidly connected with the casing 1.

Armature ring 3 is connected to or forms part of a disc the hub of which carries a spur gear, which constitutes the center wheel of a planetary gear. The outer wheel 7 of said planetary gear is formed by a spur gear which is carried by a member which is carried by the shaft 2. Said last-mentioned member is connected by means of other electromagnetically controlled planetary gears with the drive shaft; these gears are not shown as they do not form part of the present invention.

The planetary gear wheels 6 are connected with a support which is also keyed to shaft 2 and which has a hub on which the aforementioned center wheel, which forms one part with the armature 3, is revolvable and slideable in axial direction. If the windings 8 are excited while windings 10 are without current, the center wheel is held stationary. The carrier of the planetary gear wheels 6, which carrier is keyed to the shaft 2, drives then the exterior wheel 7. If, however, the windings 10 are excited and windings 8 are without current, the carrier 7 and the center wheel rotate at the same speed so that planetary wheels 6 do not rotate. The exterior gear connected with carrier 7 is then rotated at the same speed as shaft 2. Current is transmitted to the windings 8 by means of stationary sockets 9 whereas the supply of current to the

rotating electromagnets takes place through slip ring and brush.

For this purpose one end of the windings 10 is conductively connected with ring 4 whereas the other end is connected with the slip ring 11 by means of an insulated conductor 10'. Slip ring 11 is connected to the hub of the disc-shaped electromagnet having the rim 4, and isolated therefrom and has a cone-shaped configuration so that oil reaching the slip ring is removed to the left, as seen on Figure 1, by means of centrifugal forces. Brush 12 rests on the exterior surface of slip ring 11.

As is obvious from Figures 2 and 3, brush 12 consists of a tubular body of conventional material, for example a mixture of copper and coal; the bore 16 of said body widens out towards the lower end of the brush whereby an annular surface 16' is formed which contacts slip ring 11. The tubular body 12 is axially movable in the lower end of the socket 13 which may be made of metal and the upper end of which is provided with an interior thread for accommodating the adjusting screw 18.

In between screw 18 and the tubular body 12 a coil spring 17 is situated, the tension of which can be adjusted by means of the adjusting screw 18 and which presses the brush 12 to the slip ring 11. Screw 18 has a rod-like extension which extends into spring 17 for holding the windings of the latter in place.

The socket 13 carries at its upper and its lower end bushings 14' and 14 respectively made of insulating material. Bushing 14' is inserted into an opening of casing 1 whereas bushing 14 sits in a bore of a ring-shaped flange 19 which forms one piece together with the casing 1 and which serves for covering the slip ring 11 and protecting it against oil spray. On disc 21 a ring-shaped flange 20 is provided which points outwardly and is provided with an edge 20' which facilitates throwing away of oil by centrifugal forces. Edge 20' is arranged as closely as possible to flange 19 in order to prevent passage of oil towards the slip ring 11.

Above the insulating bushing 14, socket 13 is provided with radial bores 15.

The operation of the device is as follows: The revolving rim 4 and the disc 3 continuously throw oil towards the casing, which oil runs down the interior walls of the casing 1 as indicated by arrows in Figure 2. The oil also wets the exterior of socket 13 and banks up on the upper face of the insulating bushing 14. From there the oil enters the interior of socket 13 through the openings 15 and runs down within socket 13 and into the longitudinal bore 16 of the brush 12. In this manner, the oil reaches the slip ring 11 within the annular face of the brush. The small amounts of oil which pass outwardly in between the edge of the brush and the contact surface of the slip ring flow to the left, as seen on Figure 2, due to centrifugal forces and are thrown off the edge 20' so that the slip ring is uniformly covered by a thin film of oil.

Due to the funnel shaped configuration of the outer end of the bore 16, the part actually contacting the slip ring 11 is comparatively small. Experience has shown that thereby a low transition resistance is obtained and wear is reduced. This form of the brush also prevents the undesired revolving of the brush in the socket 13.

The exciting current is transmitted to the screw 18 wherefrom it flows through spring 17, holder or socket 13, brush 12, slip ring 11 and

conduit 10' into the windings 10; therefrom the current flows back through the steel mass of the magnet. The extent of the lubrication depends on and is controlled by size and number of the holes 15.

The oil flowing outwardly from the interior of the brush washes the coal dust mud away and also serves for conducting away the heat caused by the friction of the brushes on the slip ring.

For the supply of oil to the tubular brush 10 holder 13, an oil conduit 23 may be connected to the holes 15. One or more radial clearances 22 may be provided adjacent to the annular contact surface of the brush for better washing action of the oil, as are shown in Figure 3.

While I believe the above-described embodiments of my invention to be preferred embodiments, I wish it to be understood that I do not desire to be limited to the exact details of process, design, and construction shown and described, for obvious modifications will occur to a person skilled in the art.

I claim:

1. A revolving mechanism having a rotating slip ring and an electricity conducting brush, said brush having a projecting, comparatively narrow annular surface which amounts to only a small fraction of the brush cross section and which slidingly contacts said slip ring.

2. A lubricated revolving mechanism having in combination a rotating slip ring and an electricity conducting brush, said slip ring having an outer surface which is inclined with respect to the axis of rotation of said ring whereby the throwing off by centrifugal forces of lubricant reaching said ring is facilitated, said brush having a protruding and narrow annular surface which amounts to only a small fraction of the brush cross section and which slidingly contacts said inclined outer surface of said slip ring and means associated with said brush for lubricating said annular surface.

3. A revolving mechanism having a rotating slip ring and an electricity conducting brush, said brush having a cavity which widens out at one end whereby a comparatively narrow annular surface is formed which slidingly contacts said slip ring.

4. A lubricated revolving mechanism having a rotating slip ring, an electricity contacting brush, said brush being of substantially tubular configuration and having at one end an annular surface which slidingly contacts said slip ring, a tubular lubricant conduit, said brush being inserted into said conduit and slidingly movable therein, said conduit conducting lubricant into the interior of said brush, wherefrom the lubricant flows through said annular surface onto said slip ring.

5. A revolving mechanism having a rotating slip ring and an electricity conducting brush, said brush having a substantially tubular configuration, the interior of said brush being flared outwardly towards one end of the brush whereby a narrow annular surface is formed which slidingly contacts said slip ring.

6. A lubricated revolving mechanism having a rotating slip ring, an electricity conducting hollow brush, a hollow socket slidingly holding said brush in its interior and having openings through which lubricant enters the interior of said socket and therefrom the interior of said brush.

7. A lubricated revolving mechanism having a rotating slip ring, an electricity contacting brush, said brush being of substantially tubular con-

figuration and having at one end an annular surface which slidingly contacts said slip ring, a lubricant conduit connected with said brush adapted to conduct lubricant into the interior of said brush, wherefrom the lubricant flows through said annular surface onto said slip ring, stationary shielding means adjacent to said brush and revolving shielding means adjacent to said slip ring and to said stationary shielding means, 5 whereby the lubricant is prevented from reaching said slip ring except through said brush.

8. A revolving mechanism having a rotating slip ring and an electricity conducting brush, said brush having an annular surface which slidingly contacts said slip ring, said annular surface being broken, whereby lubrication and ventilation, i. e., 10 cooling of said brush is improved.

9. A lubricated revolving mechanism comprising a revolving electromagnet having windings, 15 a rotating slip ring being electrically connected with said windings, an electricity conducting brush having a bore opening out into a cavity at one end whereby a protruding narrow annular surface is formed which slidingly contacts said 20 slip ring.

10. A lubricated revolving mechanism comprising a casing which houses said mechanism, a revolving electromagnet within said casing and having windings, a rotating slip ring within said 25 casing and being electrically connected with said windings, an electricity conducting brush within 30 said casing which brush is of substantially tubular configuration and has at one end an annular surface, which slidingly contacts said slip ring, a lubricant conduit connected with said brush adapted to conduct lubricant from said casing into the interior of said brush, wherefrom the lubricant flows through said annular surface onto said slip ring, stationary shielding means adjacent to said brush and revolving shielding means connected with said electromagnets and being situated adjacent to said slip ring and to said stationary shielding means, whereby the lubricant is prevented from reaching said slip ring except through said brush.

said casing which brush is of substantially tubular configuration and has at one end an annular surface, which slidingly contacts said slip ring, a substantially tubular lubricant conduit connected with said casing and slidingly surrounding and holding said brush and being adapted to conduct lubricant from said casing into the interior of said brush, wherefrom the lubricant flows through said annular surface onto said slip ring.

11. A lubricated revolving mechanism comprising a casing which houses said mechanism, a revolving electromagnet within said casing and having windings, a rotating slip ring within said casing and being electrically connected with said windings, an electricity conducting brush within said casing which brush is of substantially tubular configuration and has at one end an annular surface, which slidingly contacts said slip ring, a lubricant conduit connected with said brush adapted to conduct lubricant from said casing into the interior of said brush, wherefrom the lubricant flows through said annular surface onto said slip ring, stationary shielding means adjacent to said brush and revolving shielding means connected with said electromagnets and being situated adjacent to said slip ring and to said stationary shielding means, whereby the lubricant is prevented from reaching said slip ring except through said brush.
